SECTIONAL METAL CONCRETE COLUMN FORM

Lowell M. Otte and Jonathan R. Merica,
Omaha, Nebr.

Application November 30, 1948, Serial No. 62,648

2 Claims. (Cl. 25—131)

1

The present invention relates to the construction of a new and improved quick setting concrete column form or the like.

An important object is to provide a simple, efficient and durable concrete column form or mold made up of interfitting adjustable metal sections or panels connected by suitable releasable means and capable of being quickly assembled or dismantled. The metal sections or members which constitute the complete column form, while preferably of the same horizontal width, are of two different vertical lengths so as to constitute sections of standard or large size and small sections having half the vertical length of the large or standard size. The column form is erected by using a pair of opposite starting forms of small sections between which are connected spaced standard size sections so that the additional sections added to the starting sections are staggered in order that the alternate adjacent sides interlock at the center of each standard size section. When the column form is completed, the large and small sections are firmly and securely held in place by retaining means to form a unitary or integral structure which may be lifted, shifted or moved about without the necessity of dismantling the sections. The sections are adjustably connected by means which conveniently permits the size of the form or mold to be varied so that the concrete columns of different quadrangular sizes and shapes may be erected by the selective adjustment of the large and small sections with each other and without requiring the use of additional sections or parts. Moreover, as the sections are held together by means inserted in the form itself, the use of clamps or other parts is dispensed with so that the completed form requires a minimum number of parts, and may be constructed and assembled at a low cost. The detachable connection of the sections with each other also provides means which, when the form is set up and before the concrete is poured in, allows the inside of the form to be cleaned out by removing one of the lower sections of the form. Additionally, since the large and small sections constituting the form or mold are rigidly and firmly connected when the form is set up, the concrete or plastic mixture may be vibrated while in the form so that in the event the concrete is not sufficiently agitated or is dry when initially introduced into the form, it may be agitated in the form so as to be thoroughly mixed and additional moisture may be added without

danger of displacing or distorting the form from its original or correct shape.

Other objects and advantages of the invention will become apparent from the following description when taken in conjunction with the accompanying claims and drawings.

Referring to the drawings in which are shown preferred embodiments the invention may assume:

10 Figure 1 is a perspective view of the metal concrete column form in its assembled position and with parts removed for the purpose of clearness of illustration.

Figure 2 is a front elevational view of one side of the assembled form.

Figure 3 is a fragmentary perspective view of the form with sections removed.

Figure 4 is a plan view of the assembled column form, and shows in dotted lines how it is adjustable to be varied in size and shape.

Figure 5 is a sectional view taken substantially along the line 5-5 of Figure 4 and

Figure 6 is a sectional view taken substantially along the line 6—6 of Figure 4.

25 Referring to the drawings in which like numer-

als indicate like parts in the several views, 10 designates the the assembled sectional metal column form or mold shaped to provide a space for receiving concrete or other suitable plastic material to form a concrete column or pier of any desired size and shape. The form 10 includes standard or large size sections or members 11 (Fig. 3) and small-size sections 12. Each section is made of sheet metal, such as steel, to

35 provide a strong and durable structure capable of withstanding the uses to which a device of this character is normally subjected, and has a smooth inner face 13 preferably formed with opposed side vertical flanges 14 (Fig. 3) that extend laterally from

40 tend laterally from the outer face 15. The smooth inner face 13 of each section or member may be crimped or formed at one end thereof to provide a chamfered surface or corner portion 16 to prevent formation of straight corners on the concrete column erected by the mold. The corner edges of the sections 11 and 12 may be straight and disposed at right angles to each other.

The standard or large size sections 11 each preferably has a vertical length of thirty-two inches and a longitudinal width of twenty-six inches. Each of the small sections or members 12 is of the same longitudinal width as the large sections 11 but has a vertical length of sixteen inches or less and about half of the length of

the large sections 11. It will, of course, be manifest that the size and dimensions of the large and small sections may be varied and the sections formed of light or heavy steel, as the particular operating conditions or use may require. To the outer face 15 of each of the small sections 12 (Fig. 3), between the vertical side flanges 14, is connected adjacent the top of the section, a transverse channel member 17 in any suitable manner such as by spot welding as at 18 (Fig. 1) so as to provide spaced outwardly extending flanges 19 and 20 which extend outwardly and laterally from the web 21 of channel member 17. The flange 19 is preferably wider than the flange 20 and the upper flange 19 is provided with transverse spaced rows of openings 22 and 23 (Fig. 3), while the inner flange 20 has a transverse row of openings 24 which register with the row 22. To the bottom or lower edge of each of the small sections or panels 12 is similarly connected a transverse channel member 25 such as by spot welding as at 26 (Fig. 1) and which is formed with an outer flange 27 of greater width than its inner flange 28. It will be seen that the edge of the channel member 25 is in transverse alignment with the lower edge of the small section 12, and that the upper channel member 17 is similar in alignment with the adjacent upper edge of this section. The outer wide flange 27 has spaced transverse rows of openings 29, while the inner flange 28 has a single row of transverse openings 30. The section 12 may be reinforced by vertically spaced channel members or straps 31 spot welded as at 32 to the outer face 15 and between the spaced inner flanges 20 and 28 of the channel members 17 and 27 (Fig. 2). Extending inwardly from one of the vertical sides 14 of the section 12 and terminating short of its opposite side and adjacent the lower and upper edges thereof, are rows of spaced transverse slots 33 and 34 which extend through the webs of the adjacent channel members 17 and 27, respectively. Extending outwardly from the opposite vertical side of the small section 12 are vertically spaced lugs 35 which may be welded to the walls of the slots 36 as at 37 (Fig. 3). The spaced lugs 35 have vertically aligned openings 38 for receiving releasable locking means 57, subsequently to be described.

Each of the standard or large sections 11 is similarly formed with a lower channel member 39 (Fig. 1) which is welded as at 40 to its outer face 15, and has an outer flange 41 and an inner flange 42 extending transversely thereof. The flange 41 has spaced transverse rows of openings 43, while the inner flange 41 has a single transverse row of openings 44. An upper channel member 45 is connected by spot welding adjacent the upper edge of the large section 11 and is likewise formed with an outer flange 46 and a narrow flange 47. The flange 46 has spaced transverse rows of vertical openings 48 and the inner flange 47 has a single transverse row of openings 49. Each of the large sections 11 has extending inwardly from one of its vertical sides and adjacent the bottom and top thereof, transverse lower and upper rows of slots 50 and 51 which extend through the webs of the adjacent channel members 39 and 45. The opposite vertical side of each of the large sections 11 has extending therefrom adjacent its top and bottom edges, spaced end lugs 52 which have aligned openings 53, and are arranged to extend through any one of the slots in the adjacent short or

long sections when these sections are superposed one on the other in order to build up or erect the form for receiving the concrete.

Additionally, each of the large sections 11, intermediate its vertical length, is provided with spaced transverse rows of slots 54 which extend inwardly from one side thereof and correspond in number to the slots 50 and 51, and are arranged in vertical registration with these slots. The opposite side of the large section 11 is provided with a pair of spaced lugs 55 in transverse alignment with the slots 54; the lugs have vertical openings 56 which register with the openings in the lugs 52. The outwardly extending perforated lugs 35, 52 and 55 in the large and small sections are of such a length as to extend through the slots in adjacent sections to receive any suitable retaining means such as the bolts or pins 57 for releasably connecting the sections together in assembling the form. To the front face of each of the large sections or panel members 11 and adjacent the center thereof are suitably connected by welding or the like, a pair of transverse abutting channel members 58 and 59 (Fig. 6) similar in construction to the channel members previously described. The channel members 58 and 59 are formed with inner transverse abutting flanges 60 and outer spaced flanges 61 of less width than the inner flanges. The flanges 60 have a double row of spaced vertical openings 62 and the flanges 61 have a single row of openings 63. Each of the channel members 58 and 59 has a transverse row of spaced slots 64 in the web thereof vertically spaced to register with one of the row slots 54 so as to receive the lugs in adjacent large or small sections when erecting the form. Vertically spaced reinforcing channel straps 65 are positioned between the flanges 61 and the flanges 42 and 47 of the channel members 39 and 45, and are welded as at 66 thereto and to the outer face 15.

In setting up or erecting the sectional mold to form a space in which the concrete or other plastic material is introduced to form a column, post, or pier of the desired quadrangular shape, two opposed small sections 12 are used as starting forms (Fig. 3) and are positioned at the point where the column is to be erected. Between the spaced sections 12 are then positioned the large spaced sections 11 which may be connected to the small sections in the following manner: One of the large sections, such as the rear section 11 shown in Figure 3, may first be secured to the left-hand small section 12 by inserting the adjacent lugs 52 and 55 through the selected spaced slots 33 and 34 in the section 12. The interfitting sections are then locked or releasably connected by inserting the retaining bolts 57 through the openings in the aligned lugs and flanges so as to firmly maintain the parts in a fixed position. The right-hand small section 12, shown in Figure 3, may then be connected through its spaced lugs 35 extending through selected slots 50 and 54, in accordance with the particular size of the concrete column to be formed. The front standard section 11 (Fig. 1) may then be connected to the right-hand small standard 12 by inserting the lower end lug 52 of the large section 11 through the selected lower slot 33 in the small section 12 and the lugs 35 on the front of the left-hand section 12 through the selected lower slot 50 and the intermediate slot 54 of the front large section 11, so that the quadrangular space thus formed will be of the desired size as the concrete

form to be erected. Then large and small sections are selectively or alternately superposed one on the other and connected together in a similar manner until the desired height of the concrete column to be formed is reached. It will be observed that the intermediate slots 54 and 64 in the large section 11 and channel members 53 and 59 may receive the lugs of either a large section or a small section, and that the intermediate lugs fit within selected aligned slots in either the large or small section of the form, in order to insure an interlocking connection of alternate sides of the section.

In building up the large and small sections, to form the mold, it will be noted that the lower wide flange of one channel member rests against the upper wide flange of an adjacent channel member to provide a firm supporting base. In order to assist in maintaining the sections in a fixed position, dowel pins 67 may be inserted through registering openings in abutting flanges such as 27 and 46 of the channel members. It will be seen that the use of clamps and other parts are dispensed with, and the sections of the forms are firmly and securely held in a fixed position by the pins 57 and 67, and that the lugs 52, 53, 55 and 56 are arranged selectively to register with complementary slots 50, 51 and 54 in adjoining or alternate sections so that the form is readily adjustable to make different size concrete columns without the necessity of using different size parts to erect different size column forms, thus materially reducing labor, cost and time in erecting the concrete form.

It will be noted that the large and small sections, as they are built up to erect the form, are staggered so that the joints 68 (Fig. 3) in the alternate or adjacent sides always interlock at the center of each large section. In other words, since the vertical length of the large sections is thirty-two inches and as the vertical length of the small sections is half this length, it will be seen that the joints 68 are broken every sixteen inches on alternate sides of the form, with the result that the form when assembled constitutes a rigid and firm unitary structure which may be lifted, or bodily moved without requiring the dismantling of any of the sections. This feature is particularly desirable since it allows vibration of the assembled form in the event that the concrete poured into the form has not been sufficiently agitated in the mixing process, or when the concrete lacks the normal amount of moisture. By reason of this unitary structure the assembled form may be vibrated to agitate the mixed concrete or water may be added to further dampen the dry concrete introduced into the form, without danger of displacing or distorting the form from its original or correct shape. A further advantage of constructing the metal concrete form of alternately disposed large and small sections when starting the erection of the form is that after the form has been set up and before the concrete is poured in, it not infrequently is necessary to clean out the space within the form. This can easily be done by removing one of the lower sections and without disturbing the other sections.

It will be seen from Figure 4 that the form may be readily adjusted by selectively connecting adjacent sections to each other through the inserting of the lugs on each section through slots in adjacent or alternate sections, so that the size and shape of the concrete column to be formed may be readily changed at a minimum

expenditure of time and effort. In this figure the form is shown in full lines to erect a large size concrete column, while in dotted lines the sections are interconnected to construct a concrete form of smaller dimensions. The inclined or chamfered members 16 are preferably used so as to provide an even finish to the concrete form and eliminate straight edges which are objectional in certain constructions as they may be readily chipped and thus mar the strength and appearance of the concrete column.

It will be seen that the metal sectional form composed of small and large sections may be economically installed and comprises a minimum number of parts and eliminates the use of separate clamps, tie rods and the like, which not only increase the cost of construction but which become lost or broken and have to be constantly replaced. Moreover, by reason of the adjustable connection of the sections to each other, concrete columns of any desired size and height may be constructed at a minimum expenditure of time and labor, and the large and small sections, after the form is initially started, may be built up either by alternate large and small sections or any other selected arrangement of the sections, so that a section will overlap each of the joints to impart desired rigidity to the assembled form.

It is to be understood that the forms of the invention shown and described are merely illustrative of preferred embodiments and that such changes may be made as come within the scope of the following claims.

We claim:

1. A metal concrete column form including interfitting and adjustably connected large and small sections, said small sections being of the same horizontal width as the large sections and not more than half of the vertical length of the large sections, each of said sections having a smooth inner face and provided with opposed vertical side flanges extending laterally from the outer face thereof, transverse channel members connected to the outer face of each section between the side flanges and adjacent the top and bottom thereof, each of said channel members having a wide outer flange and a narrow inner flange, each of said large sections intermediate its vertical length having a pair of transverse channel members connected to its outer face and provided with abutting horizontal wide flanges and spaced outer narrow flanges, the wide flanges of said channel members having inner and outer transverse rows of vertical openings and the narrow flanges of said channel members having a single row of transverse vertical openings, said sections and said channel members having spaced transverse slots extending inwardly from one side of each section, the opposite side of each section having spaced vertically aligned lugs extending outwardly therefrom and arranged to extend through slots in adjacent sections when the form is set up, said lugs having vertical holes therein, and retaining means extending through said holes and the holes in said flanges for connecting the sections together, and retaining pins extending through holes in abutting flanges of the sections for maintaining the same in a fixed position, the sections being constructed and arranged so that the form is erected by initially positioning between spaced opposed small sections, large opposed sections so that as the sections are superposed one on the other with their joints staggered, the alternate sides of the sections being interlocked at the center of each

large section by the lugs extending through aligned slots in adjacent sections to provide a rigid and firm unitary structure.

2. A metal concrete column form as called for in claim 1 in which each section has at one inner corner thereof vertically disposed means for providing when the sections are assembled, the column with chamfered corners, said sections being separately removable when the retaining means and pins are withdrawn so that any section can be taken out without disturbing the other sections to facilitate the cleaning of the column form. 5
